US0D1099889S

(12) **United States Design Patent** (10) **Patent No.:** **US D1,099,889 S**
(45) **Date of Patent:** **** Oct. 28, 2025**

(54) **NOTEBOOK COMPUTER**

(71) **Applicant:** **GETAC TECHNOLOGY CORPORATION**, New Taipei (TW)

(72) **Inventors:** **Shuan-Yeong Ju**, Taipei (TW);
Shi-Liang Zhong, Taipei (TW)

(73) **Assignee:** **GETAC TECHNOLOGY CORPORATION**, New Taipei (TW)

(**) **Term:** **15 Years**

(21) **Appl. No.:** **29/992,143**

(22) **Filed:** **Mar. 6, 2025**

(57) **CLAIM**

The ornamental design for a notebook computer as shown and described.

DESCRIPTION

FIG. 1 is a top, front, and right side axonometric view of a notebook computer, showing our new design;
FIG. 2 is a bottom, rear, and left side axonometric view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash broken lines and any unshaded surfaces in the figures illustrate the portions of the notebook computer that form no part of the claimed design.

1 Claim, 8 Drawing Sheets
